Attorney

UNITED STATES PATENT OFFICE.

MARIETTE E. EAGLETON, OF THREE RIVERS, MICHIGAN.

BAG-HOLDER.

No. 851,873.

Specification of Letters Patent.

Patented April 30, 1907.

Application filed February 11, 1907. Serial No. 356,809.

To all whom it may concern:

Be it known that I, MARIETTE E. EAGLETON, a citizen of the United States, residing at Three Rivers, in the county of St. Joseph, State of Michigan, have invented certain new and useful Improvements in Bag-Holders, of which the following is a specification, reference being had therein to the accompanying drawing.

10 This invention relates to a bag holder, and particularly to a device for supporting a bag above a jar or other vessel into which material is to be strained.

15 The invention has for an object to provide a simple and inexpensive construction and arrangement of parts by means of which a bag to be used for straining purposes may be firmly suspended above the jar or other vessel into which the material is to be strained, the same being supported by a novel arrangement of clamp secured to the edge of the jar.

20 A further object is to provide a novel construction of suspending ring for the bag by means of which the bag is held with its mouth extended so as to permit the use of both hands in the straining operation.

25 Other and further objects and advantages of the invention will be hereinafter set forth and the novel features thereof defined by the appended claims.

30 In the drawings:—Figure 1 is a perspective of the invention, and Fig. 2 is a section on the line 2—2, Fig. 1.

35 Like numerals refer to like parts in the several views of the drawing.

40 The numeral 1 designates the arms or standards which support the ring 2 from which the bag is adapted to be suspended. These arms may be formed in any desired manner or of any suitable material, but those herein shown are formed from two strands of spring wire twisted at their ends, as shown, and leaving a central loop 3 which surrounds the upper portion of the ring 2. The top 45 edge of this ring, which is preferably formed of sheet metal, is bent or rolled over the loop 3 to form a strengthening and supporting rib or shoulder 4 encircling said ring. This ring also has the hooks 5 formed therein on any 50 suitable manner, for instance by bending spurs outwardly and downwardly therefrom upon which the upper end of the bag 9 is secured. The lower ends of the arms 1 are spread apart, as shown at 6 to form a firm 55 base and each of the bifurcated ends bent

back upon itself and then downward to form the hooks or clamps 7 to engage the edge 8 of the jar or other vessel upon which the invention is to be used.

60 The advantages and usefulness of the invention will be at once apparent for it will be obvious that the twisted wire supporting arms afford a rigid and firm means for holding the bag suspending ring, while the bifurcated feet serve to hold the same against any 65 lateral displacement, and it will also be seen that these arms being formed of spring material may be attached to any width of vessel thus rendering it adjustable to fit any character of jar or dish with which it is desired to 70 use the same. The bag suspending ring also comprises a very convenient means for holding the bag for it will be observed that it is a very simple operation to attach the end of the bag to the securing hooks, and when attached this ring holds the mouth of the bag in extended position ready to receive the material to be strained thus obviating the necessity of holding the bag with one hand which permits the use of both hands to accomplish 75 the straining operation, therefore it will be seen that the invention as a whole comprises a very convenient, economical and useful utensil for use in connection with jelly making or for use in connection with other purposes where it is desired to strain material of 80 any character.

Having now described my invention and set forth its merits, what I claim and desire to secure by Letters Patent is:—

90 1. In a bag holder, a bag suspending ring, outwardly bent sharpened spurs on said ring to engage the material of the bag, and supporting arms for said ring each having laterally separated hooked ends to embrace the 95 edge of a vessel.

2. In a bag holder, a suspending ring having bag attaching means thereon, and supporting arms depending from said ring, each having a plurality of laterally separated hooked ends to embrace the edge of a vessel.

100 3. In a bag holder, a bag suspending ring having hooks thereon to engage the material of the bag, supporting arms for said ring formed of twisted strands, the central portion of said strands being formed into a loop surrounding said ring, and the ends of said strands being separated and formed into hooks to engage the edge of the vessel.

105 4. In a bag holder, a bag suspending ring

having its upper edge flanged, supporting arms for said ring formed of twisted strands the central portion of said strands being formed into a loop to be engaged by the 5 flange on said ring and the ends of said strand being separated and formed into hooks to engage the edge of the vessel.

In testimony whereof I affix my signature in presence of two witnesses.

MARIETTE E. EAGLETON.
